UNITED STATES PATENT OFFICE.

IRVIN R. BLOSE, OF SHARON, PENNSYLVANIA, ASSIGNOR OF ONE-HALF TO WILLIAM DIXON, OF MARTINS FERRY, OHIO.

ROLLING-MILL.

1,150,492.

Specification of Letters Patent. Patented Aug. 17, 1915.

Application filed July 30, 1913. Serial No. 782,054.

To all whom it may concern:

Be it known that I, IRVIN R. BLOSE, a citizen of the United States, residing at Sharon, in the county of Mercer and State 5 of Pennsylvania, have invented certain new and useful Improvements in Rolling-Mills, of which the following is a specification.

This invention relates to certain new and useful improvements in roll polishers, and 10 relates particularly to a polisher for metal rolls such as are used in tin mills, sheet mills, plate mills or the like, in which sheets, plates, bars or the like are rolled.

The invention has for its main object the 15 provision of roll polishers which may be employed for polishing rolls during their operation without in any manner interfering with their operation or the operator.

The further object of this invention, is 20 the provision of means whereby the emery stone or other polishing substance while in normally constant contact with the rolls may readily be changed to any position where polishing for that moment is desirable.

25 A still further object, is the arrangement of the suspension means for the upper polisher in such a manner that upon the breaking of a roll, the device will not be injured.

Still further objects and purposes of this 30 invention will appear from the drawings, the specifications describing the same and the claims appended thereto, in which are more fully set forth the arrangement of parts, combination of elements and specific structural details comprised within the 35 scope of the same.

In the drawings in which is shown a preferred embodiment of my invention, Figure 40 1 is a front elevation of the housing, with rolls therein and my invention applied thereto, (housing being shown with irrelevant portions omitted). Fig. 2, is a sectional side elevation taken on line XX of Fig. 1, and looking from left to right on Fig. 1, (that portion of the apparatus at the right of the housing in Fig. 1, being shown in dotted lines). Fig. 3, is a perspective view showing a fragmentary section of one of the housings, the relation of 45 the rolls thereto and the method of attachment of the retaining means for the upper polisher. Figs. 4 and 5 are fragmentary detail views illustrating the bifurcated ends of 50 one of the cross rods and one of the cross rod supporting arms, respectively.

Referring now to the several figures in which like reference characters designate like parts; 1 represents the housing; 2 the base plate; 3 the upper roll; 4 the lower roll. The rolls are provided with ordinary 60 wobbler connections 5.

6 indicates the usual foreplate, the supporting means of which however, are omitted in the drawing.

At the front inner portion of each housing, adjacent the point of contact of the rolls, I provide brackets 7; in the brackets are journaled the short shafts 8, these shafts at their inner ends are provided with the upwardly curved arms 9, 9'. These arms are 65 positioned adjacent the inner faces of the 70 housings so that they are out of the line of feed of material to the rolls and their upper ends are substantially above the plane of the foreplate. In a similar manner, I provide arms 10, which extend downwardly 75 from the inner ends of the shafts 8 so that their ends lie below the foreplate and line of feed of material to the rolls. The outer ends of the shafts 8 are provided with gears 80 11. These gears mesh with gears 13, which have bearings in blocks 12 positioned in front of the outer ends of the shafts 8. Rigidly secured to the sides of the gears 13 85 are the forwardly extending levers 14 from the outer ends of which are suspended the weights 15 by means of helical springs which afford resilient connections between the levers and the weights and absorb any sudden shocks and jars which may be imposed on the machine during the operation 90 thereof.

The upper ends of the arms 9, 9' are provided with slots 16, in which the rectangular slide bar 17 rests. The rod 17 is fastened at its left end to the upper end of arm 9' by means of the bolt 19, while it is dependent solely upon its position within the slot for its connection to the upper end of the arm 9. 95

Slidably mounted upon the bar 17 is the holder 18, which is adapted to receive the emery or other abrasive block 18'.

Integrally extending from the inner and lower ends of the arms 10 are horizontal extensions 10' 10''. 105

A rod 20 is fixedly secured at one end to the forward end of 10', while the other end of said rod is bifurcated as at 20' so as to receive the forward end of the member 10'', 110

the connection being such as to permit the separation of the member 10" and the rod 20 in event of the side movement of either housing.

5 Secured to the rod 20 is the downwardly extending foot lever 21, which is preferably positioned to the left of the middle of the rod.

10 On the inner forward side of each housing at the base, I secure bearing blocks 22, journaled in the rear upper portion of these blocks is the bar 23. Rigidly fixed on either end of this bar, adjacent the blocks, are the gears 24, which mesh with gears 26 of corresponding size. The latter are mounted 15 upon trunnions 25, having bearings in the blocks 22.

20 Extending outwardly from and having fixed connection with the trunnions 25 and gears 26 are the levers 27, from the outer ends of which are suitably suspended the weights 28 by means of helical springs. As apparent from the drawings, the rod 23 between its points of bearing in the blocks 22 is rectangular in cross section. Slidably 25 mounted on this rod 23 is the vertically positioned arm 29, provided at its upper end with means for holding the emery or other abrasive material. Attached to this holder 30 at a point adjacent the slide is a continuous cable 30 which passes over four pulleys positioned as shown more clearly in Fig. 1, so that the top stretch of the cable is beneath the forward part of the foreplate and 35 readily accessible to the roller.

Extending downwardly from the right side of the bar 23 is a foot lever 32.

40 In operation, my invention operates as follows: The weights 15 acting through the gears 11 and 13, press the arms 9 9' and the polishing block carried thereby against the upper roll. In same manner, the weight 28 acting through the gears 24 and 26 press the polishing block against the lower roll. 45 When the roller desires to change the position of either one of the polishing blocks, the left foot lever is pressed rearwardly in the case of the upper polishing blocks, and the right foot lever pressed rearwardly in 50 the case of the lower polishing block. When the left lever is pressed, the rod 20 and extensions 10', 10", the gears 11 and the arms 9 9' move away from the roll and in opposition to the weights 15. While the 55 rod 17 is thus held away from the roll, the roller may slide the polishing block holder 18 to any desired position on the bar 17, and upon releasing the foot lever 21, the polishing of the desired place begins. When 60 the roller presses the right foot lever 32 toward the rear, the slide bar 23 and the arm 29 is swung away from the roll in opposition to the weight 28. The roller may now grasp the cable 30 at its upper and forward part, which it will be observed is

just under the forward part of the foreplate and readily accessible to the operator, and by moving the portion grasped either to the right or left, slide the polishing block 29 a corresponding distance in the opposite direction. The release of the foot lever 32 then allows the block to be thrown back against the lower roll. 70

It must of course be understood that instead of employing the weights 15 and 28, 75 I may use any other suitable counterbalancing devices, the effect of which may be increased or decreased in any well known manner, and with like effect as in the present case when the size of the weights are 80 changed.

It will be observed that in the present device, all elements are so located as to be entirely out of the road of either the roller or catcher, and while they do not interfere 85 with the rolling of the material, yet are so positioned as to be easily and instantaneously operable by the roller, the man charged with the operation of the mill, without loss of his time or the efficiency of the 90 mill.

As is well known, roll breakage is more or less inevitable, and must be provided for in rolling mill equipment. Upon the breaking of a roll, the housings tend to separate. 95 To prevent destruction of the apparatus in event of the breaking of a roll, I have so secured the right end of the slide 17 and bar 20 in the arm 9 and 10" respectively, as to permit the endwise withdrawal of the 100 former without any damage to the apparatus. In the case of the bar 23, if the housing spreads at this point, one end of the bar will merely be withdrawn from its bearing block 22. 105

I claim,

1. In a rolling mill, the combination of rolls, a polishing block slidably mounted in front of each roll, independent means pressing each of said blocks against its roll, and means operable independently in opposition to the first means to withdraw a block from its roll. 110

2. In a rolling mill, the combination of 115 housings, rolls journaled therein, shafts carried by the forward portions of said housings, block holders carried by said shafts, means located forward of the shafts for rotating them and the holders carried thereby toward the rolls, and other means acting 120 on the shafts below the point of action thereon of the former means for rotating said shafts and the holders carried thereby away from the rolls.

3. In a rolling mill, the combination of 125 housings, rolls journaled therein, shafts rotatably mounted in the forward portions of said housings, polishing blocks carried thereby, means located forward of said shafts for rotating them in one direction, 130

and other means for rotating said shafts in the opposite direction.

4. In a rolling mill, the combination of 5 housings, rolls journaled therein, shafts rotatably mounted in the forward portions of said housings, polishing blocks carried thereby, means located forward of said shafts for rotating them in one direction, and other means located in the forward part of the 10 mill for rotating said shafts in the opposite direction.

5. In a rolling mill, the combination of 15 housings, rolls journaled therein, a pair of short shafts journaled on the housings below and forward of the upper roll, an upwardly curved arm extending from the inner end of each shaft, a bar carried in the upper ends of said arms, a polishing block slidably carried by said bar, means acting upon said 20 shafts to rotate them and the arms thereon toward the upper roll, and means acting upon said shafts to rotate them and the arms carried thereby away from the upper roll.

6. In a rolling mill, the combination of 25 housings, rolls journaled therein, a slidably mounted polishing block normally pressed against the upper roll, means operable from the front of the mill for withdrawing said block from the roll, a slidably mounted polishing block normally pressed against the 30 lower roll, and other means operable from the front of the mill for withdrawing the block from the lower roll.

7. In a rolling mill, the combination of 35 housings, rolls journaled therein, a bar journaled in the lower front portion of the mill, a polishing block holder slidably mounted upon said bar, means for rotating said bar and holder carried thereby toward the lower 40 roll, and a foot lever operable from a point forward of said bar for rotating the bar and holder carried thereby away from said roll.

8. In a rolling mill, the combination of

45 housings, two rolls journaled therein, a foreplate in front of said rolls, polishing blocks normally pressed against said rolls and means operable independently for withdrawing the block from either roll, the whole of said means being located substantially below the foreplate.

50 9. In a rolling mill, the combination of housings, rolls journaled therein, a foreplate in front of the rolls, a plurality of shafts rotatably mounted in the housings, polishing blocks adapted to move toward the rolls 55 by the rotation of the shafts in one direction, and means for rotating said shafts in the other direction whereby the blocks are withdrawn from the rolls, substantially the whole of said means between the housings 60 lying below the foreplate.

10. In a rolling mill, the combination of housings, rolls journaled therein, a foreplate in front of the rolls, a bar rotatably mounted below said foreplate, a polishing block 65 holder slidably mounted thereon, and an endless cable secured to said holder and passing adjacent the forward edge of the foreplate.

11. In a rolling mill, the combination of 70 housings, rolls journaled therein, a pair of shafts rotatably mounted on said housings, two connections between said shafts, each of said connections comprising a pair of arms and an interposed bar, each connection having a slotted joint between two adjacent elements thereof whereby said shafts are disconnected upon the lateral movement of either one, and a polishing block holder mounted on one of said bars.

75 In testimony whereof I affix my signature in presence of two witnesses.

IRVIN BLOSE.
